LIQUID CONTAINER.

Bruce A. Jackson, Oakland, Calif.

Application January 7, 1938, Serial No. 183,870

4 Claims. (Cl. 215—31)

The present invention relates to liquid containers and particularly to the novel construction and arrangement of the mouth and rim of such containers.

Many liquid containers, particularly bottles of various kinds and shapes, have rims at their mouths which are thicker in section than any other portion excepting only the bottom portions. It is the rim of the container which is most subject to chipping and damage and which if damaged destroys its further usefulness. In addition to other things the extra thickness provided constitutes reenforcement of this vulnerable place and some measure of safety against damage from external blows. If the container is to have usefulness either in the first instance or in reuse, precaution in the form of reenforcing of the rim must usually be taken. Further, the chipping and the damaging of the rim at the mouth of the container come most usually from angular and horizontal blows and therefore it has been the practice in the arrangement of the reenforcing to eliminate angles and sharp edges and to provide curves so that blows may be deflected. This is perhaps best exemplified by the large bead at the rim of the ordinary milk bottles.

It is also well-known that soft drink and other beverage containers in particular, have a roll or bead at the rim of the bottle, which, in addition to the reenforcing of the container rim, aids the securing of the capping or closure means. Certain medicine bottles and containers for toilet supplies have capping and closure means which similarly utilize the bead reenforcing at the mouth of the container.

It is an object of this invention to provide a liquid container which utilizes the benefits and advantages of the reenforcing rim such as beads or rolls and yet one from which liquids may be poured with facility and ease without the drops and dribbling running down the outside of the container.

It is another object of this invention to provide a reenforced bottle rim which will likewise provide adequate pouring means in bottles and containers suitable for laboratory and medicinal use in which neither the reenforcement of the bottle rim nor the elimination of dribbling is sacrificed one for the other or minimized in any way but rather where each is actually facilitated.

Many efforts have been directed to providing the rims of containers, particularly glass bottles, with spouts for pouring. These efforts in general have taken two forms. The first form employs a projecting spout of one shape or another

which accomplishes the pouring without dribbling but materially accentuates the danger of chipping and breaking. Projecting as it does without adequate reenforcing the breaking off of the spout is almost a certainty. Also, in commercial production, where machines and equipment are geared to a uniform sized container rim, projecting spouts and the like are wholly impracticable. For these reasons, as well as others, the first form is quite generally regarded as unsatisfactory. The second form employs dents or cut-outs in the rim. This latter form, however, has been considered impractical up until the present time because of the inability to retain the reenforcement of the rim and at the same time adequately eliminate the dribbling.

It is a further object of this invention to provide a container with adequate reenforcement at the rim and secure pouring or dispensing without dribbling or the like, all being accomplished without projecting spouts or similar means.

Another object of the invention is the production of a liquid container with a reenforcing protected rim having twin pouring spouts either singly or in multiple, wherein the larger phase directs the full flow and the smaller phase the limited or thin flow.

It is a further object of the invention to provide a limited or controlled flow from a liquid container which has a rim of larger section for the most part than any other portion thereof normally has excepting the base or bottom portion.

Further objects are to provide a construction of maximum simplicity and economy and such further objects, advantages and capabilities as will later more fully appear and as are inherently possessed thereby.

The invention further resides in a construction and arrangement of parts illustrated in the accompanying single sheet of drawing and while there is shown therein a preferred embodiment and a modification thereof, it is to be understood that the same are capable of further modification and change and comprehend other details and constructions without departing from the spirit of the invention.

Referring now to the drawing:

Fig. 1 is a top plan view of the rim portion only of a container;

Fig. 2 is a similar view showing the twin flow diagrammatically;

Fig. 3 is a fragmentary vertical section of the top portion of the container taken on the line III—III of Fig. 1;

Fig. 4 is a fragmentary view partly in section and partly in elevation taken on the line IV—IV of Fig. 1 and looking in the direction of the arrows; and

5 Fig. 5 is a view in perspective of a portion of the pouring lip and container rim.

Like reference numerals are used to designate similar parts in the drawing and in the description of the invention which follows.

10 Referring now particularly to the drawing, 10 represents the upper portion of a container made of glass or any other suitable material.

While my invention will be described in connection with a container made of glass, it is obvious that the invention lends itself as well for 15 use in containers made from tin or any other material.

At the mouth of the container there is provided one or more segments of a beaded or rolled rim 20 11. The segments 11 are of larger cross-section than ordinarily found in any portion of the container save only the bottom portion and provide the reinforcement of the rim of the container. The outermost surfaces 14 of the segments preferably are all equidistant and on the same radius with respect to the longitudinal axis of the container. The height of the segments 11 is preferably uniform to present an even surface to the closure means where such closure is a cap or 30 crimp bottle top or even the beverage type top. The bead or roll overhangs the neck 10 at 13 a sufficient distance to permit the unchanged use of such closure means. If desired, there need be but one continuous segment spaced apart at its 35 ends to form a single pouring opening.

The ends of the segments 11, regardless of their number, when viewed in plan as in Fig. 1, are shaped with a comparatively flat curve 18 sweeping toward the outside surface 14, but just before 40 the outer surface 14 is reached, the curve becomes sharper.

The space provided between ends 18 of segments 11 is joined by a pouring floor 15 which may be made integral with segments 11 at its 45 sides and with the rim. Pouring floor 15 extends from the inner rim 12 of the container outlet, from which point it gradually narrows. From here it extends upwardly along the curved surfaces 18 of segments 11 and then drops down 50 substantially vertically between these ends 18 until it reaches a small bead or shelf 19. The width of floor 15 at this point is preferably narrow so that the upper flat floor 21 of bead 19 combines with the end portions 22 of segment 55 curves 18 to provide a four walled pocket.

In actual practice I have found that the bead 19 should be semi-circular in cross-section with a diameter approximately one-eighth of an inch,—also, that the bead 19 should be set outwardly from wall 10 of the container neck so as to provide horizontal under surface 13 at the bottom of rim 11. Pouring floor 15 is recessed inwardly from the outside surface 14 of the rim 11 for the purposes herein set out. It is also set lower than the top of rim 11.

The ends 18 of the segments 11 serve as protection for the pouring floor 15 and the bead 19 as well, and also as guides for the flow of liquid through this channel.

70 Further, the segments 11 may be dished or cupped as at 20 on the inner surface at either side of the channel 15 and adjacent thereto. The purpose of this is to form a second pouring spout. This cupping may be varied to accommodate any 75 desired degree of flow larger than possible

through the channel between ends 18. The effect of this form is to control the full flow of liquid when more than the amount capable of flowing through floor 15 is required. When this larger flow is diminished, the liquid poured is 5 accommodated by channel 15, is confined in and is controlled by the channel and its bead 19. In this manner a twin flow spout is provided. As better illustrating the meaning and effect of twin flow and twin flow spouts, reference is here 10 made to Fig. 2, where the lines A represent the stream outline and level when controlled through channel 15, and where the lines B represent the larger stream outline and level when controlled by surfaces 20.

Obviously, a single segment 11 providing a single pouring floor 15 may be made in the rim of a container, or a plurality of segments forming a plurality of spouts may likewise be provided, making it unnecessary to rotate the container any appreciable distance in order to bring a spout into proper position. Either construction provides multiple twin flow spouts for the container.

The operation of my invention is as follows: 25 Regardless of whether or not a large or small quantity of liquid is to be poured from the container, the form of the pouring floor 15 and its associated bead 19 will be brought into play. The cupped or dished portions 20 on rim 11 will 30 be brought into play when there is to be a full or rapid emptying of the container contents.

Assuming that the container is substantially filled to the rim 12, and that it is desired to withdraw very slowly a portion only of the contents, 35 if the container is tilted, the liquid begins to flow over floor 15 confined between walls 18 and 22. With the container in this filled condition, the tilt will not at first be sufficient to cause the liquid to fall away from the floor 15 until it has reached 40 the bead 19. If the container is now set upright, the liquid remaining on the floor 15 will either flow back into the container or will flow down the floor 15 onto the bead and drop into the receptacle receiving the liquid. The small portion 45 remaining on the floor 15 will be collected at the junction of floor 15, floor 21 and sides 22. I have found from experiment that with bead 19 made about one-eighth of an inch in diameter, any residue remaining on the bottom of the bead will 50 not pass along under surface 13 and down onto neck 10, but will either drop off bead 19 or will be drawn back up with the liquid remaining on floor 55 21 between sides 22 and ends 18.

Assuming again that the container is substantially filled to the rim 12 and that it is desired to empty a substantial portion of its contents fairly rapidly, the container is tipped and the liquid assumes a level such as indicated by B in Fig. 2, and the flow of the stream controlled by 60 dished portions 20 on the rim will be substantially as indicated by the outer lines shown in Fig. 2. As the flow diminishes, it will drop to the point where it is controlled entirely by the pouring floor 15 and sides 18 as shown by the lines A in 65 Fig. 2. As the flow decreases still further, the condition described above will take place and there will be practically no tendency for the liquid remaining on the floor 15 to spill or dribble.

While the drawing illustrates a plurality of 70 pouring floors 15 and of segments 11, it is to be understood that my invention is capable of being practiced where there is but a single pouring floor and the rim 11 is continuous except for the opening on each side of the floor. Also, while the 75

drawing illustrates a container made of glass, the use of other materials is contemplated.

What I claim is:

- 5 1. In a container, having a pouring outlet, the combination of upstanding wall portions extending above the level of said outlet, a relatively narrow pouring channel formed at the bottom of the space between adjacent ends of said wall portions, said channel extending down the outside of the container outlet rim where it terminates in an outwardly projecting bead, to form a pocket at the terminus of said channel.
- 10 2. In a container having a pouring outlet, the combination of a plurality of upstanding wall portions extending above the level of said outlet, a relatively narrow pouring channel formed at the bottom of the space between adjacent ends of said wall portions, said channel extending down the outside of the container outlet rim where it
- 15 terminates in an outwardly projecting bead.
- 20

spaced between the bordering pair of wall portions, to form a pocket near the terminus of said channel.

3. In a container having a pouring outlet, the combination of an upstanding wall portion surrounding said outlet, a relatively narrow channel formed in the outer vertical face of said wall portion, said channel extending downwardly from the top thereof, a bead connecting adjacent wall sections of said wall portion, said bead extending across the bottom of said channel to provide a pocket.

4. In a container having a pouring outlet, the combination of an upstanding wall portion surrounding said outlet, a channel extending down the outside of said wall portion and an outwardly projecting bead to form a pocket at the terminus of said channel.
